(57) **CLAIM**

The ornamental design for a screw as shown and described.

DESCRIPTION

FIG. 1 is a perspective view of the screw embodying the new design;
FIG. 2 is a right side view thereof;

FIG. 3 is a left side view thereof;

FIG. 4 is a top view thereof;

FIG. 5 is a bottom view thereof; and,

FIG. 6 is a section cut view of the top portion of the screw, taken along the line 6-6 of FIG. 5.

The jagged line along the bottom of FIG. 6 represents the boundary of the detail cut away view. The broken lines in FIGS. 1-3 illustrate that the portion of the screw between the broken lines forms no part of the claimed design. The brackets in FIGS. 1-3 indicate the portion of the screw between the broken lines, and form no part of the claimed design. The broken lines in the drawings illustrate portions of the screw and form no part of the claimed design.
